To all whom it may concern:

Be it known that I, HERBERT S. On the drawing:

Figure 1 is a front view of the impact bar.

Figure 2 is a plan view of the impact bar,

one of the ends of the bar being shown in section so as to more clearly illustrate the spoon-shaped contour of the same.

Figure 3 is an enlarged end view of the impact bar taken from the left hand side of Figure 2; both ends of the bar, however, being of the same shape and design.

I claim:

The ornamental design for an impact bar for automobile bumpers, as shown, and described.
